FURNITURE LEG BRACKET

Edward E. Schaefer, River Forest, Ill.

Application March 15, 1956, Serial No. 40,620

Term of patent 14 years

(Cl. D33—14)

Fig. 1 is a side elevational view of a furniture leg bracket, showing my new design.

Fig. 2 is a top plan view of the bracket shown in Fig. 1.

Fig. 3 is a side elevational view of the bracket in inverted position relative to Fig. 1.

Fig. 4 is a top plan view of the bracket as shown in Fig. 3.

Fig. 5 is an end view as seen from the left in Fig. 1.

Fig. 6 is an end view as seen from the right in Fig. 1.

Fig. 7 is an enlarged cross-sectional view as taken along the line 7—7 of Fig. 6.

I claim:

The ornamental design for a furniture leg bracket, substantially as shown.
